UNITED STATES PATENT OFFICE.

FRANK J. LEMIEUX, OF CENTRAL FALLS, RHODE ISLAND.

PISTON.

Application filed January 4, 1927. Serial No. 158,887.

This invention relates to certain new and useful improvements in pistons particularly serviceable in connection with internal combustion engines, but capable of general use 5 for other kinds of engines, pumps and the like.

More particularly, the invention embodies an improved piston comprising a hollow cylindrical body portion adapted to be carried 10 by a piston rod or connecting rod, and a head detachably secured to the body portion to permit ready removal or placement of a packing ring or rings without requiring undue expansion of the latter or removal of 15 the body portion from the rod or working cylinder.

A further object is to provide a sectional piston capable of being readily taken apart for convenient removal or replacement of 20 the packing ring thereof.

A still further object is to provide a sectional piston of the above kind which is extremely simple and durable in construction, as well as efficient in operation.

25 Another object is to provide simple and effective means for detachably connecting parts of the piston for maintaining the latter in operative condition.

Still another object is to provide simple 30 and effective means for locking the parts in assembled relation in such manner that the same will not become accidentally disconnected under ordinary conditions of use, although being capable of ready intentional disconnection.

Other objects will become apparent as the 35 nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

45 Figure 1 is a developed perspective view showing all of the parts of the piston in the relation in which they are assembled.

Figure 2 is a side elevational view of the piston in assembled condition; and

50 Figure 3 is a central longitudinal section taken substantially upon line 3—3 of Figure 2.

Referring more in detail to the drawings, the present piston embodies what may be 55 generally termed as a hollow cylindrical body portion composed of an inner section

5 and preferably two ring-like packing rings receiving and spacing sections 6 and 7, and a head or cap plate 8 detachably connected to the section 5 and retaining the sections 60 6 and 7 in place.

As shown clearly in Figures 1 and 3, the inner section 5 is formed with an outer end wall 9, and a skirt here shown as embodying a pair of opposed segmental sections 10 65 having oppositely disposed inwardly projecting bearings 11 adapted to carry a wrist pin for the connecting rod, the pin and rod not being shown as they operate in the usual well known manner. It will be seen that 70 the bearings 11 integrally join with the underside of the wall 9 so as to present a strong, durable construction. While it is desirable to cut away the skirt as shown so that it is composed of similar opposed segmental sections 10, it is nevertheless to be 75 understood that the skirt may be of continuous form as usual, such cutting away of the skirt being merely practised to somewhat reduce the weight of the piston when 80 found desirable.

The wall 9 of the section 5 is uniformly 85 reduced in diameter at its outer end so as to form a relatively short cylindrical extension 12 onto which the ring receiving and spacing section 6 is removably fitted, the engaging surfaces of these parts being smooth so as to permit them to be slidably engaged or disengaged. In a like manner, the section 6 is formed with a reduced outer end to provide a cylindrical extension 13 on which the inner end of section 7 is removably fitted, while the section 7 is formed with a further similar cylindrical extension 14 onto which 90 is removably fitted the inwardly projecting 95 cylindrical packing ring receiving portion 15 of the head or cap plate 8.

The sections 6 and 7 are provided with 100 peripheral packing ring spacing flanges or ribs 16 and 17 of annular form, the flange 16 cooperating with the wall 9 to form inner 105 packing ring receiving grooves, the flange 17 cooperating with the flange 16 to form an intermediate packing ring receiving groove, and the head or cap plate 8 being provided with a peripheral annular flange 18 outwardly of the packing ring receiving portion 15 thereof, cooperating with the flange 17 to form an outer packing ring receiving groove.

110 The outer end wall 9 of the inner section 5 is formed with an axial outwardly project-

ing internally threaded hollow boss 19 adapted for threaded reception of an externally threaded axial stem or stud 20 formed integral with and projecting inwardly from the head or cap plate 8. Thus, when the several parts are assembled in the relation shown and described above and the head 8 is rotated relative to the section 5 so as to thread the stem 20 into the boss 19, the head will be detachably connected to the inner section 5, and the several parts will be drawn into tight contiguous relation with the sections 6 and 7 and the packing ring effectively retained in place. It will be apparent that by reason of the interfitting engagement of the sections, they will all be properly entered and retained in this proper relation when assembled.

In order to effectively guard against accidental turning of the head and threading of the stem 20 out of the boss 19 such as would result in separation of the piston sections, releasable means is provided for locking the stem 20 to the boss 19. This locking means preferably consists in the provision of a longitudinal threaded internal groove 21 in the boss 19 and a complementary groove 22 exteriorly of and longitudinally in the stem 20, said groove 21 being adapted for registry with the groove 22 when the piston parts are assembled for reception of a locking screw 23. In order to permit ready insertion of and access to the locking screw 23, the head 8 is provided with an opening 24 therethrough communicating with the groove 22 and adapted to communicate with the groove 21 when the latter is registered with groove 22 as noted above. It is thus apparent that the grooves 21 and 22 cooperate to form a threaded socket into which the screw 23 is threaded upon insertion through the opening 24 in the piston head section 8, and as the socket is partially formed in the integral parts of the head and section 5, relative turning of these parts will be effectively prevented. This locking is made additionally secure by adapting the opening 24 to receive the head of screw 23, and peening the material of the head 8 over the head of screw 23 as at 25 so that the screw 23 may not accidentally back out of the grooves 21 and 22 when the piston is in use. However, this peened over material may be readily displaced when the screw 23 is forcibly turned by the use of a screwdriver, and it will not, accordingly, interfere with the intentional separation of the piston sections or parts. In order to better guard against loss of compression, the grooves 21 and 22 preferably terminate outwardly of the inner end of stem 20 as shown in Figure 3.

From the above, it will be seen that when the head of the cylinder in which the pistons

operate is removed, the screw 23 is readily accessible for removal, and in order to permit subsequent turning of the head 8 for its removal without disconnecting the body 5 from the connecting rod or removing it from the cylinder, said head 8 is equipped with sockets 26 in its outer surface for reception of the driving contacts of a spanner wrench or the like. It will be noted that the boss 19 is considerably spaced from the sections 6 and 7 so that an annular closed air space is formed in the outer end of the piston that will tend to avoid overheating of the piston when in use.

Upon removal of the head 8 as outlined above, it will be seen that the outer packing ring may be readily removed from the portion 15 of the head and a new ring placed thereon, while similar free removal of the sections 6 and 7 and their respective packing rings is also permitted. A reversal of this operation will effect convenient and expeditious re-assembling of the parts.

It is apparent that the construction is of a most simple and durable character and involves a minimum number of parts, none of which are frail or likely to readily become damaged or broken.

As shown in Figures 1 and 3, the wall 9 is provided with a circular series of obliquely extending openings or passages 27 which extend from the inner side of the innermost packing ring receiving groove to the interior of the inner section or body section 5. These passages or openings 27 provide efficient means for conducting lubricant or oil to and from the faces of the cylinder and piston when in use, and one passage 27 communicates with the interior of each bearing 11 so as to insure a proper supply of lubricant to the latter. The passages leading to the bearings 11 are clearly shown in Figure 3.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:

A piston comprising a body part having an outwardly extending, central, internally threaded boss, and a cap having an externally threaded stem fitted to said boss, said cap being spaced from said body part for the reception of superposed annular ring holding members and said members being spaced from said boss, a substantial distance and providing a closed air space to prevent undue heating of the piston.

In testimony whereof I affix my signature.
FRANK J. LEMIEUX.
